UNITED STATES PATENT OFFICE

126,824

DESIGN FOR AN ELECTRODE FOR A
THERAPEUTIC MACHINE

Carl K. Gieringer, Cincinnati, Ohio, assignor to
The Liebel Flarsheim Company, Cincinnati,
Ohio, a corporation of Ohio

Application July 16, 1940, Serial No. 93,672

Term of patent 7 years

To all whom it may concern:

Be it known that I, Carl K. Gieringer, a citizen of the United States, residing at Cincinnati, in the county of Hamilton and State of Ohio, have invented a new, original, and ornamental Design for an Electrode for a Therapeutic Machine, of which the following is a specification, reference being had to the accompanying drawing, forming a part thereof.

Figure 1 is a perspective view of an electrode for a therapeutic machine showing my new design.

Figure 2 is a perspective view looking toward the face of the electrode.

Figure 3 is a top plan view.

The characteristic feature of the design resides in the smooth, rounded inner edges and the bead which borders the outer surface, all as shown.

I claim:

The ornamental design for an electrode for a therapeutic machine, substantially as shown and described.

CARL K. GIERINGER.
